HARRY A. SILVERMAN, OF NEW YORK, N. Y.

PERFORATING-IRON.

1,401,821.

Specification of Letters Patent. Patented Dec. 27, 1921.

Application filed May 21, 1920. Serial No. 383,108.

To all whom it may concern:

Be it known that I, HARRY A. SILVERMAN, a citizen of the United States, residing in the borough of Bronx, city and State of New York, have invented an Improvement in Perforating-Irons, of which the following is a specification.

This invention relates to a perforating iron adapted to be used in perforating material preferably in sheets along predetermined lines in making patterns and other similar articles. I am aware that heretofore various forms of devices have been used for this purpose and my invention relates more particularly to that type of such devices in which the perforating points of the apparatus are heated to a sufficient extent to cause a clean or smooth edged hole or perforation to be made in the material in the use of the tool. In some instances more or less complicated devices have been employed for heating perforating irons electrically and in order to overcome these complications and reduce the cost of manufacture at the same time obtaining the same results, I propose to employ an iron comprising a frame in which there is revolvably mounted a wheel having a toothed or serrated edge together with means for heating the wheel so that the serrated edge is maintained at an adequate temperature to properly perforate the material in making the pattern. The apparatus also includes an adjustable foot for determining the position of the teeth of the iron and consequently the size of the perforation which is made in the material in the manufacture of the pattern. In the invention as hereinafter more particularly described the perforating wheel is preferably mounted in a frame through which a suitable gas is supplied and burned adjacent the heating member of the iron to maintain the same at the required temperature, while the perforating member is mounted and secured in place in the parts which form the wheel.

In the drawing:

Figure 1 is a central longitudinal cross section illustrating a perforating iron made in accordance with this invention, and

Fig. 2 is a side elevation of the same.

In the construction of the perforating iron made in accordance with this invention, I employ a handle 10 through which there is passed a feed pipe 11 for supplying gas or other inflammable fluid for heating the iron.

At one end of the handle this feed pipe is

preferably divided to form a frame in which the parts of the iron are revolvably mounted. The frame therefore comprises the branch pipes 12 and 13 which form a yoke or frame 60 in which the iron is placed. The outer portions of these branch pipes are substantially parallel and closed at their extremities and on their inner portions provided respectively with lugs 14 and 15 forming bearings for 65 the revolvable parts of the iron as hereinafter described, the lugs 14 and 15 being hollow and the spaces therein communicating with the interior of the branch pipes in order that the gas or other fluid employed may 70 flow freely from the pipes to the interior of the lugs to be emitted therefrom, as hereinafter described, and burned to heat the perforating member of the iron.

The revolvable parts of the iron, as clearly 75 illustrated in the drawing, preferably include a disk perforating member 16 which is made of iron or any other suitable material and provided with a serrated periphery, the teeth 17 of which form the means for puncturing or perforating the material from which the pattern is made. At the sides of the disk 16 I may employ washers 18 and 19 made of asbestos or any other similar heat insulating material, and exteriorly of the 80 washers there are cover plates 20 and 21. The cover plate 20 preferably comprises a hub 22 with ribs or spokes 23 extending therefrom and connecting the same to a flange or rim 24, the hub 22 being adapted 85 to be received on the lug 14. Similarly the cover plate 21 comprises a hub 25 with ribs or spokes 26 extending therefrom and connecting the hub with a flange or rim 27, the hub 25 being adapted to be received and to 90 turn on the lug 15. The diameters of the rims 24 and 27 and the washers 18 and 19 are substantially the same. The rims 24 and 27 and the washers 18 and 19 with the disk 16 intervening between the washers are 100 connected by bolts 28 passing through the same or in any other desired manner. These parts when thus connected comprise a wheel structure which is journaled on the lugs 14 and 15 so as to turn within the yoke frame 105 to which the handle is connected.

At the inner or adjacent ends thereof the lugs 14 and 15 are provided centrally with apertures 29 and 30 forming orifices from which the gas is emitted from the spaces or 110 chambers within the lugs so that the gas may be ignited and burned from these ori-

fices with the flames directly inwardly or toward each other so as to heat the disk 16 which at its central portion for this purpose is preferably reinforced as indicated 5 at 31.

Connected to and extending from the supply pipe 11 is a tube 32. In this is slidably mounted a rod 33 connected to a foot or guide member 34, it being adjustable to position 10 relatively to the serrated edge of the disk by shifting the position of the rod in the tube and securing the parts in place by a set screw 35 or otherwise. As is clearly shown in the drawing the foot member is 15 provided with a slot 36 through which the teeth or serrated edge of the disk may be made to extend so as to determine the extent to which the teeth enters the material of which the pattern is to be made and 20 consequently the size of the perforations outlining the pattern.

In the use of the hereinbefore constructed perforating iron acetylene or any other form of gas or vaporized hydro-carbon from 25 any suitable source may be supplied to the pipe 11 through a hose 37 or otherwise and the gas after passing through the supply pipe and its branches forming the frame for the revoluble parts of the iron is made to 30 burn at the orifices 29 and 30 as hereinbefore described to heat the disk 16 to the required temperature for causing the desired clean cut perforations to be made by the 35 heated teeth at the periphery of the iron in passing the same over the material to be perforated in making the pattern.

I claim as my invention:

1. A perforating apparatus comprising a revoluble member having a serrated edge, 40 and a frame including a yoke and bearings on which the revoluble member is journaled and through which yoke and the said bearings gas is supplied to heat the revoluble member.

45 2. A perforating apparatus comprising a revoluble member having a serrated periphery, a gas supply pipe, and a tubular yoke frame extending from the supply pipe and in which the said revoluble member is 50 mounted and through which gas is supplied to the said revoluble member to heat the same.

3. A perforating apparatus comprising a disk having its periphery serrated to form 55 perforating teeth, cover members connected to the said disk, and a yoke frame in which the said cover members and disk are jour-

naled and through which gas is supplied to the said disk to heat the same.

4. A perforating apparatus comprising a 60 disk having a serrated edge, cover plates on both sides of the said disk, means for connecting the said disk in said cover plates, and a tubular yoke frame in which said cover plates are mounted and through which 65 and the said cover plates gas is supplied to heat the said disk.

5. A perforating apparatus comprising a 70 disk having a serrated edge, cover plates on both sides of the said disk, means for connecting the said disk in the said cover plates, and a tubular yoke frame having lugs on the inner faces of the branches of the yoke and upon which the said cover plates are 75 mounted and through which from the said tubular yoke gas is supplied to heat the said disk.

6. A perforating apparatus comprising a 80 disk having a serrated edge, cover plates on both sides of the said disk, heat insulating washers on both sides of the disk, cover plates on both sides of the heat insulating washers, bolts extending through the cover plates, the said washers and the disk to maintain the said parts in an assembled 85 relationship, and a tubular yoke frame having lugs on the inner faces of the branches thereof and upon which the said cover plates are journaled, through which lugs from the 90 tubular yoke gas is supplied to heat the said disk.

7. A perforating apparatus comprising a 95 revoluble member having a serrated periphery, a gas supply pipe, a tubular yoke frame extending from the supply pipe and in which the said revoluble member is mounted and through which gas is supplied to the 100 said revoluble member to heat the same, a guide member, and means for adjusting the same to position to determine the extent of the perforation made by the apparatus.

8. A perforating apparatus comprising a 105 disk having a serrated edge, cover plates on both sides of the said disk, means for connecting the said disk in the said cover plates, a tubular yoke frame in which said cover plates are mounted and through which and the said cover plates gas is supplied to heat the said disk, a guide member, and means for adjusting the same to position to determine the extent of the perforation made by the apparatus.

Signed by me this 14th day of May, 1920.
HARRY A. SILVERMAN.
